UNITED STATES PATENT OFFICE.

E. A. ANDREWS, OF NEW BRITAIN, CONNECTICUT.

TRUNK-HANDLE.

Specification of Letters Patent No. 7,981, dated March 18, 1851.

To all whom it may concern:

Be it known that I, ELIJAH A. ANDREWS, of New Britain, in the county of Hartford and State of Connecticut, have invented a new and useful Improvement in Lifting-Handles for Trunks and other Articles; and I do hereby declare that the following is a full, clear, and exact description of the construction and operation of the same, reference being had to the accompanying drawings, which make a part of this specification, in which—

Figure 1, is a perspective view of one of the lifting handles, complete, showing the movable part as it hangs down by its own weight. Fig. 2, is a perspective view of the same, showing the movable part turned up, as when lifting by it. Fig. 3, is a perspective view of the plate, or stationary part, showing the spaces in which the journals of the movable parts are inserted and held. Fig. 4, is a perspective view of the movable part, showing the journals &c.

My improvement consists in casting the lifting handle in two part, complete, so that when taken from the mold the movable part may be slipped into the spaces in the plate, or stationary part, and immediately attached to any piece of furniture, for use, without any riveting, or otherwise fastening the parts together.

I make the stationary part, A, Figs. 3, 2, and 1, of cast iron, or other suitable metal, of any desired shape, (ornamental or plain,) with two raised, and hollow parts, B and B', Fig. 3, &c., to receive the ends, or journals, of the movable part, C, as seen in Figs. 1, and 2. Under, or behind, these projections, B, and B', are slots, or spaces, open through the plate, A, as seen at α , and α' , Fig. 3. These projections are so shaped that they will hold the journal of the movable part in the proper position for use, as seen in Fig. 2, or at rest, as seen in Fig. 1, while the handle is attached to the trunk, or other

piece of furniture, &c., but when the handle is not attached to any article, the movable part, C, may be attached to, or detached from, the stationary part, A, at pleasure.

I make the movable part, C, Figs. 1, 2, 50 and 4, of cast iron, or other metal, in the ordinary shape, with journals on the ends, as seen at b and b' , Fig. 4. Having thus cast the two parts, I insert the end, b , of the movable part, Fig. 4, through the slot, 55 or space, α , Fig. 3, a sufficient distance to allow the end, b' , to fall into the slot, or space, α' , when by drawing back the end, b , the two parts will be attached together, as seen in Figs. 1, and 2, when the handle is 60 ready to be attached to a trunk, or other article, by screws, or otherwise.

The parts may be finished in any of the ways of which cast metal is susceptible, as by varnishing, polishing, galvanizing, &c., 65 when desired.

The advantages of my improvement, over all other methods, consist in casting the two parts in such shape that they may be put together, at once, by the hands, without 70 any alteration of either of the parts, or the use of any tools whatever, (unless it be desired to finish the parts for ornament,) so that the parts may be taken from the mold, put together, attached to a trunk, and used, 75 before the metal has had time to get cold.

What I claim as my invention, and desire to secure by Letters Patent, is

Casting the article in two parts in such a form that they may be put together without any alteration of the parts, and so that they can not get out of place when the handle is attached to a trunk or other article, when the whole is constructed substantially, as herein described.

ELIJAH A. ANDREWS.
